DESIGN FOR A CABINET FOR SOUND RECEIVING AND TRANSMITTING APPARATUS

Fred L. Meagher, New York, N. Y., assignor to
Jordanoff Corporation, New York, N. Y., a corporation of New York

Application September 12, 1947, Serial No. 141,345

Term of patent 3½ years

(Cl. D56—4)

To all whom it may concern:

Be it known that I, Fred L. Meagher, a citizen of the United States, residing at New York, in the county and State of New York, have invented a new, original, and ornamental Design for a Cabinet for Sound Receiving and Transmitting Apparatus, of which the following is a specification, reference being had to the accompanying drawing, form a part thereof.

In the drawing:

Fig. 1 is a front elevational view of a cabinet for sound receiving and transmitting apparatus, showing my new design;

Fig. 2 is a side elevational view; and
Fig. 3 is a top plan view thereof.

I claim:

The ornamental design for a cabinet for sound receiving and transmitting apparatus, substantially as shown.

FRED L. MEAGHER.
